SAFETY GUARD FOR BUFFING MACHINES.

John M. Kelly, Adrian, Mich., assignor to Gerity-Michigan Corporation, Adrian, Mich., a corporation of Michigan

Application March 22, 1947, Serial No. 736,486

5 Claims. (Cl. 51—268)

1

This invention relates to a buffing wheel safety guard and assembled mechanism for use preferably with pneumatic systems in which the dust is suitably removed, and I provide means to stop and collect any article (if dropped out of the buffer's hands) thereby avoiding possible injury to the workmen, the guard also acting to prevent dust fumes, etcetera, from being directed toward the workmen.

In certain types of buffing wheels, the actual buffing material on the revolving wheel wears relatively rapidly and my invention provides means to readily and accurately adjust and keep in set position the buffing guard of my invention in proper position in the mechanism.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure I is a top plan view of one embodiment of my guard screen;

Figure II is a top plan view of the same installed in the channels for supporting the same in the hood of the buffer mechanism;

Figure III is a rear side elevational view of the mechanism installed with the buffing wheel and hood parts broken away to illustrate the construction;

Figure IV is a side elevational view of the assembly with parts broken away to show the operating mechanism;

Figure V is a front elevational view of the removable drawer at the bottom of the hood; and

Figure VI is an elevational view partly in section of the gearing mechanism for adjusting the guard screen, or plate.

As shown in Figure IV, my present invention includes an adjustable guard 10 for use assembled in the dust hood 12 which surrounds the buffing wheel 14, driven in the direction of the arrow 15. Connected with hood 12 is a pneumatic duct 16, through which dust from the buffing operation is drawn by the blower system (not shown).

As stated above, the present invention is intended to be applied to machines for buffing plated material such as chrome plated articles of all kinds including those of various shapes and sizes, some of which are relatively small and if

2

the operator drops one of the pieces, the guard 10 will prevent the same from being carried around by the wheel 14 and thrown out through the top of the hood 12 which might fly right into the operator's face who is standing facing the wheel 14. Moreover, as the material on the buffing wheel is continually wearing, it is necessary to adjust the guard 10 toward the center of the wheel as the diameter thereof decreases due to such wear, which in some instances may be relatively rapid.

In Figure I, I show the guard 10 detached from the mechanism, and in this instance the same comprises a frame 18 to which is attached the wire mesh 20. The guard material 20 may be made of solid sheet metal, if desired, and it is to be understood that this guard "locked" in position, as shown in Figure IV, will aid in directing more dust out through the air duct 16 due to the suction of the blower system.

To apply the guard 10 to the machine, I secure on opposite sides of the hood 12 a pair of angle or channel irons 22 and 23 located at an angle as indicated in Figure IV. The guard 10 slides in these angle plates in any position of adjustment as determined by the adjusting mechanism. As indicated in Figure II, I provide a pair of transverse braces 24 and 25 connected with the angle irons 22 and 23 to give rigidity to the assembly of the mechanism in the hood 12.

As indicated in Figure I, the guard 10 is provided with a series of longitudinally arranged openings 28 and 29 on the opposite sides of the guard to operate as gear racks with which a pair of gears 30 and 31, shown in Figure VI, are fixed on rotatable shaft 33, and are adapted to cooperate with and operate said racks 28 and 29 on the guard 10. As indicated in Figure VI, the shaft 33 is rotatably supported in bearings 34 and 35, supported on the underside of angle pieces 23 and 22. The shaft 33 extending outside of the buffing hood 12 and having connected on its outer extremity the worm wheel 36. It will thus be seen that by providing means to rotate the shaft 45 33 through the worm wheel 36, the gears 30 and 31 acting through the racks 29 and 28 will slide the guard 10 in the channels 22 and 23 to any position desired.

So that the operator may readily adjust the guard, I provide on the outside of the hood a worm 38 carried by worm shaft 39 which is suitably mounted in brackets 40 and 41 to the outside of the hood 12 as indicated in Figures III and IV. The upper end of the worm shaft 39 is 55 provided with an operating handle 43 extending

up above the top of the dust hood 12 so that the operator may be able to readily adjust the handle 43 and turn the shaft 39 in one direction or the other to move the guard plate or screen 10 toward or away from the buffing wheel 14.

An important feature of my invention resides in the simplification of the assembly and operating parts of the adjustable guard 10 and particularly by the improvement of the worm wheel 36 operated from worm 38, the pitch of the teeth may be made so that the parts will automatically stay in any particular position of adjustment due to the friction, and yet on the other hand, the adjustment of the position of the guard plate or screen 10 may be made to a fine degree as may be required.

As indicated in Figures IV and V, the bottom of the hood 12 is provided with the sliding drawer 45 having a suitable handle 46 so that the same may be pulled outwardly to retrieve any small articles that may have been dropped by the operator, carried around by the buffing wheel 14 to hit the guard 10 and drop down the hood 12 and into the sliding drawer 45. It will be understood that the mesh of the screen 20 on the guard 10 is made relatively small but of a very strong weave so as to effectively divert any articles down the hood 12 into the drawer 45 and as stated a solid plate 20 may be used.

I claim:

1. A buffing wheel guard in combination with a hood and pneumatic dust removing system, comprising a guard supporting means secured within the hood rearwardly of the buffing wheel, a guard located within said hood and supported by said means; a transverse rotatable drive shaft located within said hood and extending outside thereof; gearing between said shaft and said guard adapted to operate and move said guard to various positions of adjustment; a gear fixed to said transverse shaft and located outside said hood; a cooperating gearing and shaft mounted on the outside of the hood for turning said transverse shaft, said shaft extending to the top of the hood; and a means connected with the upper end of said shaft whereby the operator may operate the mechanism to adjust said guard in said hood.

2. A buffing wheel guard in combination with a hood and pneumatic dust removing system, comprising a guard supporting means secured within the hood below the center of and rearwardly of the buffing wheel axis, a guard located within said hood and supported by said means; a transverse rotatable drive shaft located within said hood and extending outside thereof; gearing between said shaft and said guard adapted to operate and move said guard to various positions of adjustment; a friction gear means fixed to said transverse shaft and located outside the hood; a cooperating gearing and shaft mounted on the outside of the hood for turning said transverse shaft, said mechanism operating to maintain said guard in set position of adjustment.

3. A buffing wheel guard in combination with a hood and pneumatic dust removing system, comprising a guard supporting means secured

within the hood below the center of and rearwardly of the buffing wheel axis, a guard located within said hood and supported by said means; a transverse rotatable drive shaft located within said hood and extending outside thereof; gearing between said shaft and said guard adapted to operate and move said guard to various positions of adjustment; a gear fixed to said transverse shaft and located outside the hood; a cooperating gearing and shaft mounted on the outside of the hood for turning said transverse shaft; said hood extending to the floor; and a removable drawer at the bottom of said hood for receiving articles directed downwardly of said hood by said guard.

4. A buffing wheel guard in combination with a hood and pneumatic dust removing system, comprising a pair of rails adapted to be secured within the hood below the center of and rearwardly of the buffing wheel axis, a guard having parallel gear racks on opposite sides, said sides located within said rails; a transverse shaft; gears carried by said shaft adapted to operate said racks and move said guard; a worm wheel fixed to said transverse shaft located outside the hood; a worm and worm shaft mounted on the outside of the hood for turning said worm wheel, said worm shaft extending to the top of the hood; and a crank handle connected with the upper end of said shaft whereby the operator may adjust said guard within said hood.

5. A buffing wheel guard in combination with a hood and pneumatic dust removing system, comprising a pair of rails adapted to be secured within the hood below the center of and rearwardly of the buffing wheel axis, a guard having parallel side members; a series of holes in said members adapted to constitute gear racks; on opposite sides of said guard, said side members located within said rails; bearings carried by said rails on the underside thereof; a transverse shaft rotatably mounted in said bearings; gears carried by said shaft adapted to operate said racks and move said guard; a worm wheel fixed to said transverse shaft located outside the hood; a worm and worm shaft mounted on the outside of the hood for turning said worm wheel, and means connected with said shaft whereby the operator may adjust said dust guard within said hood.
